UNITED STATES PATENT OFFICE.

ROBERT ALBERTSON, OF CHICAGO, ILLINOIS.

DESIGN FOR A COMBINED LECTERN AND BOOK-CONSOLE.

48,879.

Specification for Design.

Patented Apr. 18, 1916.

Application filed November 3, 1915. Serial No. 59,484. Term of patent 14 years.

To all whom it may concern:

Be it known that I, ROBERT ALBERTSON, a citizen of the United States, residing at Chicago, in the county of Cook and State of Illinois, have invented a new, original, and ornamental Design for a Combined Lectern and Book-Console, of which the following is a specification, reference being had to the accompanying drawings, forming a part thereof.

In the drawings—Figure 1 is a front ele-

vation; Fig. 2 is a rear elevation; Fig. 3 is a righthand side elevation; and Fig. 4 is a perspective of a device showing my design.

I claim:

The ornamental design for a combined lectern and book-console as shown.

ROBERT ALBERTSON.
